LIQUID FUEL FEEDING DEVICE FOR INTERNAL COMBUSTION ENGINES

Raymond Leslie Kent, Marston Green, near Birmingham, and Murray Duncan Scott, Bury Green, Cheshunt, England

Application November 3, 1936, Serial No. 109,038
In Great Britain November 8, 1935

3 Claims. (Cl. 261—50)

This invention relates to fuel lift carburettors for use wherein the main fuel supply reservoir is normally located at a level below that of the carburettor, and the carburettor is designed to produce a depression capable of raising the fuel from the reservoir level to that of the carburettor.

There have been numerous attempts to produce a carburettor of this type by utilizing a venturi to step up or multiply the engine suction so that the depression created within the carburettor is sufficient at all times to raise fuel from the low level reservoir to the carburettor.

The difficulty has, however, been to select a venturi or venturis which is or are capable both of meeting the condition that the engine cylinders must be adequately filled at low engine speeds with full throttle opening and that still gives a sufficient multiplication factor to raise fuel. Or, in other words, if the size of the venturi is sufficient to provide the least possible resistance to the flow of mixture at all speeds under full throttle opening conditions, it will not at all speeds be found capable of creating sufficient depression to lift the fuel thereto. On the other hand, when employing a venturi of comparatively smaller size which is capable of raising fuel at all engine speeds, it will be found that when the throttle is fully opened at high engine speeds the demand upon the venturi is too great to enable it to maintain a sufficient supply of mixture to the engine.

We have found in accordance with this invention that by employing a venturi whose cross sectional area is capable of variation that it is possible so to arrange for a substantially constant relationship to be obtained between the depression existing on the engine side of the carburettor and that existing at some predetermined point or section in the axis of the venturi, the depression obtained at this point or section being used to raise fuel from a reservoir situated below the level of the carburettor, and furthermore remaining substantially at the minimum value sufficient for this purpose.

According to this invention therefore a fuel lift carburettor device for internal combustion engines comprises the combination of a low level fuel supply reservoir and a carburettor apparatus having a fuel intake chamber at a level above the reservoir, a jet orifice or orifices, to which fuel is supplied from the intake chamber, a jet needle or other means for controlling the amount of fuel passing the jet orifice or orifices, a venturi, the effective cross sectional area of

which is so capable of variation as to give a normal Venturi action in all its positions of adjustment and a pressure responsive member responsive to the depression produced in the venturi, which depression is also transmitted to the intake chamber to raise fuel from the low level reservoir, and means actuated by the pressure responsive member for causing adjustments in the cross sectional area of the venturi and for controlling the position of the jet needle or other jet control means.

Thus the resultant cross sectional area of the venturi with reference to axial length will, in our invention, give a variation similar to that of a normal venturi so that whatever the position of adjustment, there will be an unbroken streamline flow through the venturi without turbulent effect. Preferably, the venturi is composed of two relatively moving male and female parts of such configurations that in any relative position of the two parts, the resultant cross sectional area will, as just stated, give a normal Venturi action, i. e., an unbroken streamline flow.

The variable venturi may consist of a stationary member of conventional Venturi design, fitted with an axially movable tapered member, movable by the pressure responsive member, the members being so arranged and designed that at all times the depression at some predetermined section is at a maximum in relation to the depression existing between this composite venturi and the induction ports of the engine.

The tapered member may be formed integrally with a piston constituting the pressure responsive member, the piston being mounted in a cylinder to which the depression created by the venturi is transmitted.

One embodiment of the invention is illustrated in the accompanying drawing which is a sectional lay-out of a fuel feeding device embodying a venturi whose cross-section is capable of variation, the moving parts being shown in their slow running or at rest position with the entrance to the venturi closed or substantially closed.

Referring to the drawing, 1 indicates part of the throttle or intake pipe to the engine in which is the usual throttle valve 2. In the intake pipe 1 is a venturi 7, the depression at the front of which is transmitted to a needle controlled jet 3 and to a fuel intake or float chamber 4 and also to a pressure responsive member 5, which controls the size of the jet opening through a needle valve 26 and also operates a choke member 6.

The choke piece 6 is movable under the control of the member 5 in relation to the venturi 1, so as in effect to constitute a venturi of variable cross-section as herein described.

5 The parts just described are shown in their slow running or at rest position with the entrance to the venturi throat closed or substantially closed. It is an essential feature of the invention that the pressure responsive member 10 is so constructed and arranged that it will only operate to permit the opening of the choke when the depression created in the system is sufficient to raise fuel under all conditions.

In operation, when the engine crank shaft is 15 rotated for the purpose of starting, and the throttle valve 2 partly opened, the depression produced will be communicated through the venturi to the jet 3 and to the float chamber and the depression created therein will be sufficient 20 to raise fuel from the supply tank.

25 As previously stated the pressure responsive member is so loaded that until the depression created is sufficient to raise fuel into the fuel chamber, it will not operate to raise the choke member 6 and thus permit the opening of the choke.

30 Fuel on entering the intake chamber will flow to the jet where it is mixed with a small quantity of air, the emulsion so formed passing 35 into the venturi throat whence it is drawn into the engine as an explosive mixture.

To describe the embodiment of the invention illustrated, in detail it comprises a two part casting, the lower half of which is indicated at 38 8 and the upper part at 9. In the lower part 8 is a bore 10, which is a continuation of the throttle pipe. A bore 11 of the same size is provided in the upper portion 9 of the casting, but which is provided also with an enlarged bore 12 constituting a cylinder, in which is slidably mounted 40 the pressure responsive member in the form of a piston 13. The piston 13 is not a perfectly air tight fit in its cylinder.

45 A sleeve 14 inserted in the bores 10, 11 serves to spigot together the two parts of the casting, which are bolted together along their meeting faces in which as is hereinafter described are provided the feed passages to the venturi throat.

50 The interior of the sleeve 14 is shaped to constitute the venturi 1 and it will be observed that part of the wall of the cylinder 12 is cut away as at 15 to enable the admission of air to the downstream end of the venturi, when the choke 55 piece 6, which is tapered, has been moved upwards by the pressure responsive member against the action of a spring 16.

The spring 16 is held in position against a detachable cover plate 17 for the cylinder 12.

60 The employment of a return spring, while not essential has the advantage that it enables a reduction in the mass of the piston so that there is a smaller tendency for the position of the piston to vary on rough roads.

65 The float chamber 4 is incorporated in the lower part 8 of the casting and is provided with an inlet pipe 18 from the feed tank (not shown). 19 is a float controlling a cut-off valve indicated generally at 20 so that when the chamber is full the admission of liquid fuel is prevented.

70 Petrol from the chamber 4 passes through a feed passage 21, to a jet chamber 22, which is formed as an enlargement of a bore 23 extending 75 through both parts of the casting. In the

bore 23 is mounted the needle valve 26, one end of which is provided with a flanged head 24 for engagement with an annular groove 25 in the piston 13. It will be observed that suction induced by the engine draws the fuel upwardly past the jet 3 from the jet chamber 22, the jet discharge mixing with air drawn down the bore 21, the emulsion so formed being drawn up the annular space between the needle 26 and the bore 23 and passing thence to the venturi.

10 It will be appreciated therefore that as the piston 13 rises and falls the needle valve 26 will move with it and so increase or decrease the size of the (main) jet opening. The jet 3 may be held in position by means of a spring (not 15 shown), one end of which bears against the screw plug 22' closing the jet chamber 22.

15 In the throat of the venturi are a number of holes 27 giving access to an outer groove 28 which is fed through two diametrically opposed 20 ducts 29 extending into an annular groove 30 formed in the meeting face of the casting 8 and into one side of which groove the bore 23 merges.

25 The depression in the system is transmitted to the cylinder 12 containing the piston 13 through a bore 31 which at one end opens into the bore 23 and at its other end communicates through a port 32 with the cylinder top.

30 The fit of the piston 13 within the cylinder is such as to provide a certain leakage but in order to reduce the effect of variation in the piston clearance which would vary the amount of air bleed, an additional bleed hole 33 to the atmosphere is provided.

35 In some cases it may be desirable to provide a damping action to delay the initial movement of the piston and for this purpose an annular groove 34 is cut in the cylinder wall for communication with the bore 31 the effect of which is to create an air seal round the piston.

40 When the piston is damped in this manner it may also be desirable to provide for a rapid movement of the piston through a small portion of its travel from its lower or rest position. This may be effected by means of a port 35 communicating with the interior of the cylinder at a point immediately above the rim of the piston 13. The port 35 will also operate to prevent the piston from being sucked downwards when the throttle is first opened owing to the depression 45 acting immediately on the nose of the piston before it has a chance of acting on the top as it would if the full damping were in action.

45 A turn cock 36 may be provided for controlling the strength of the mixture and starting when 55 the engine is cold. It will be obvious that by turning the cock 36 to the position shown it will restrict the passage 31 and so cause a pressure drop resulting in a difference in depression between the choke and the float chamber thereby 60 increasing the amount of suction on the jet.

55 Since it may not always be convenient to adjust the main jet opening a subsidiary jet 37 is provided by-passing the main jet, the size of the subsidiary jet being adjustable by means of 65 a needle valve 38 actuated by a screw 39 having a milled head.

60 The float chamber 4 may be connected to the cylinder 12 by means of a passage 40 in order that any lag in the movement of the piston during acceleration will result in a temporary increase in the pressure drop across the jet.

70 As previously stated the fuel intake to the venturi through the holes 27 is located at a point upstream of the point of minimum cross- 75

section of the female member and thus nearer the entrance end of the venturi, since by so positioning the intake it simplifies the design of the venturi and choke member 6 which will give a true Venturi action at all speeds and thus secure a multiplication of the depression, which is substantially constant for all positions of the choke member.

An essential feature of this invention is to provide a venturi of variable cross section which at all speeds will produce sufficient depression to lift fuel under the most adverse conditions normally encountered without imposing sufficient restriction on the inflowing mixture to cause appreciable loss of power.

Previously, self-feeding carburettor constructions have been proposed with a large Venturi area having some form of controllable obstruction below the throat, but with this arrangement the venturi is not properly effective unless the obstruction is removed out of the way, so that at low engine speeds, the depression created by the venturi will not be sufficient to maintain the requisite supply of fuel or mixture to the engine, the reason being that the multiplying effect of a venturi varies with its shape, thus, if the intake is obstructed, the pressure drop or depression set up in the system will be mainly due to the obstruction, and only in a minor degree due to the drop across the Venturi throat. In other words, by simply obstructing the intake the depression in the system will be the result of the depression due to the obstruction plus the multiplied depression produced by the drop across the Venturi throat. If the former is relatively large, the combined multiplication factor of the whole system will be considerably less than that obtainable with a simple venturi.

If instead a small venturi is employed, the depression, provided the venturi is small enough, would always be multiplied to an extent such as to ensure a sufficient supply of fuel to the engine. It will be found, however, that the amount of fuel that has to be passed through it in order to satisfy the engine requirements will have the effect of drowning it and so decreasing the suction effect, with the result that the multiplication factor of the venturi will be considerably reduced. Therefore, since the unmultiplied vacuum in the engine manifold is inadequate to raise fuel under all conditions unless it is made high enough to affect the power of the engine adversely, it is the object of this invention to provide a venturi which, under all conditions of operation, is of the correct size according to existing conditions to pass the amount of air and fuel required by the engine at full load. We have, therefore, found that by employing a venturi having two relatively moving parts 6 and 7, of such cross sectional outline that in any relative position of the two parts their difference in cross sectional area in the direction of the axis of flow will correspond to the cross sectional area of a normal venturi for that particular set of conditions. Since the multiplying effect of a venturi is governed by the rate of change of cross sectional area along its axis, the respective members forming the venturi should be so shaped that the difference between the squares of their diameters at various axial positions should in any of the positions of the parts diminish progressively towards the point of minimum cross sectional area of the resultant passage and increase thereafter towards the engine at a small or preferably smaller rate.

We have also found that this set of conditions can more easily be secured by arranging for the fuel and/or depression intake of the venturi to be not at the point of smallest cross section of the female member but at a point upstream thereof and thus nearer to the entrance. As hereinafter described, therefore, we thus arrange the fuel intake through holes located at a point upstream of the point of minimum diameter of the female member.

As previously stated, the fuel intake to the venturi through the holes 27 is located at a point upstream of the point of minimum cross section of the female member and thus nearer the entrance end of the venturi, since by so positioning the intake it simplifies the design of the venturi and choke member 6 which will give a true Venturi action at all speeds, and thus secure a multiplication of the depression, which is substantially constant for all positions of the choke member.

The operation of the device will be clear from the foregoing description, but to recapitulate, when the engine is at rest the piston 13 which is at its lowest position in the cylinder 12 is so arranged that the choke member 6 integral therewith almost completely closes the venturi 1. At this time the needle valve 26 will also be at its lowest position so as to afford the maximum obstruction to the jet nozzle. On starting up the engine, when the throttle is partly opened, the suction caused thereby will be transmitted through the Venturi throat and feed passages and via the bores 23 and 40 to the float chamber when fuel will be drawn in from the supply 18.

Fuel upon entering the chamber will flow down the passage 21 into the chamber 22 and thence be drawn through the jet 3 where it will mix with air drawn in from the bleed hole 33 and past the piston. The emulsion of fuel and air 40 will now pass up the feed passages into the venturi where it will mix with further air and be drawn into the engine as an explosive mixture. On further opening of the throttle the depression originally created in the system will be built up until it is sufficient to raise the piston 13 against its spring 16 thereby withdrawing the choke member 6 and increasing the effective cross-sectional area of the venturi increasing the opening of and simultaneously opening the jet 50 orifice 2.

For convenience it may be assumed that a float chamber depression equal to 2 lbs. per square inch will be needed to aspirate fuel into the float chamber under the most arduous conditions.

Under these circumstances, the weight of the piston should be such that a depression of 2 pounds per square inch acting upon its upper surface would just fail to raise it so as to ensure that under all conditions fuel will be aspirated into the float chamber.

By the provision of the venturi of variable cross section, we ensure the building up of a depression of sufficient magnitude in the various passages described and in the float chamber 66 so as to raise fuel, notwithstanding the position which the piston may occupy in response to any particular throttle opening, this state of affairs being maintained with a depression at the base of the venturi or the induction pipe of such a small magnitude as to have no appreciable adverse effect upon the power output of an engine.

What we claim is:

1. A fuel raising and carburetting device for use in internal combustion engines, comprising

5 a fuel chamber, mixture passage including a Venturi tube, a pressure responsive member, means placing said member and the fuel chamber in communication with the throat of the venturi, a fuel jet including a jet opening and a
10 needle valve for controlling the effective area thereof, means connecting the jet opening on one side thereof to the venturi and on the other side to the fuel chamber, and a choke piece movable into and out of the Venturi throat to vary the choke opening, both the needle valve and choke piece being actuated by the pressure responsive member which is so restrained that it will cause a depression in the system sufficient
15 to raise fuel to the fuel chamber before it increases the jet and choke openings.

2. In a fuel raising and carburetting device for use in internal combustion engines, the combination of a fuel chamber, a fluid pressure responsive member, a fuel jet including a movable element shaped to vary the area of opening thereof according to its position, a variable choke comprising a venturi having a throat and a choke member carried by the pressure responsive member and movable into and out of a position within the Venturi throat to vary the choke
25

opening, means providing communication between said Venturi throat and said fuel chamber for establishing low pressure in said chamber for lifting fuel thereto and for providing communication between said Venturi throat and said pressure responsive member for actuating the latter, the fuel jet movable element being movable through movement of the choke member, said pressure responsive member being actively responsive to pressure in the Venturi 10 throat to move said jet movable element to increase the extent of opening of the fuel jet and to move said choke member to increase the extent of the opening of the throat only when the pressure in the fuel chamber has been lowered 15 to a point at which it is capable of raising fuel to said chamber under normal conditions, conduit means between the fuel chamber and the pressure responsive member, and an adjustable control valve in said conduit. 20

3. A device as claimed in claim 1 in which the first means has its orifice at a point upstream of the narrowest section of said venturi. 25
